CLAIM

The ornamental design for a foldable knife, as shown and described.

DESCRIPTION

FIG. 1 is a top perspective view of a foldable knife showing my new design, wherein the blade is in the open position;

FIG. 2 is a bottom perspective view of FIG. 1;

FIG. 3 is a top plan view of FIG. 1;

FIG. 4 is a bottom plan view of FIG. 1;

FIG. 5 is a front elevation view of FIG. 1;

FIG. 6 is a rear elevation view of FIG. 1;

FIG. 7 is a right side elevation view of FIG. 1; and,

FIG. 8 is a left side elevation view of FIG. 1.

The knife blade is depicted in broken line form because it is not considered part of the claimed design.
